(57) **CLAIM**

The ornamental design for a heated floor runner, as shown and described.

DESCRIPTION

FIG. 1 is a top right perspective view of a heated floor runner showing my new design; and

FIG. 2 is a top elevational view thereof,

FIG. 3 is a left side elevational view thereof,

FIG. 4 is a right side elevational view thereof,

FIG. 5 is a front end elevational view thereof; and,

FIG. 6 is the back end elevational view thereof.

The broken lines depict portions of the article that form no part of the claimed design.
